Attn:

UNITED STATES PATENT OFFICE.

JOHN F. WILLIAMS, OF KANSAS CITY, KANSAS, ASSIGNOR TO THE ECONOMY GAS LAMP COMPANY, OF KANSAS CITY, MISSOURI.

DESIGN FOR A LAMP-FIXTURE.

SPECIFICATION forming part of Design No. 30,147, dated February 7, 1899.

Application filed December 24, 1898. Serial No. 700,289. Term of patent 14 years.

To all whom it may concern:

Be it known that I, JOHN F. WILLIAMS, a citizen of the United States, residing at Kansas City, in the county of Wyandotte and State of Kansas, have invented and produced a new and original Design for a Lamp-Fixture, of which the following is a specification.

My present invention relates to a new and original design for lamp-fixtures, of which the following is a specification, reference being had to the annexed drawing, wherein the frame is shown in elevation.

The fixture consists of two curved arms A and B, connected at their upper ends to a fitting or casting C, from which extends a straight section D. A reservoir E is mounted upon said section D, and a hook F extends up from the reservoir. To the lower end of arm B there is fixed a fitting or casting G, and from the horizontal branch of the fitting extends an arm H, which stops just short of

a projection I, extending out from a coupling or casting J, secured to the lower end of arm A. Extending down from the coupling G is an arm K, its lower end being bent at right angles, forming a horizontal arm L. A similar arm M extends down from coupling J and is formed with a horizontal arm N, the ends of the arms L and N being connected to a casting or fitting O, which forms the burner-support.

Having thus described by invention, what I claim is—

The design for a lamp-fixture as herein shown and described.

In witness whereof I hereunto set my hand in the presence of two witnesses.

JOHN F. WILLIAMS.
